UNITED STATES PATENT OFFICE.

WALTER OPEL, OF LEIPZIG, GERMANY.

SOUND-BOX FOR TALKING-MACHINES.

1,229,780.

Specification of Letters Patent. Patented June 12, 1917.

Application filed March 5, 1915. Serial No. 12,237.

To all whom it may concern:

Be it known that I, WALTER OPEL, a citizen of Germany, and a resident of Leipzig, Saxony, State of Germany, have invented 5 certain new and useful Improvements in or relating to Sound-Boxes for Talking-Machines, of which the following is a specification.

In order to increase or to weaken the tone 10 action in talking machines use is made in connection with the sound-box of needles of appropriately greater or smaller thickness. It is, therefore, necessary to interrupt the playing when an alteration in the tone is to 15 be obtained. Moreover, the exchange of the needles is not only costly but frequently results in inconveniences. Experiments have been made with a view to changing the tone action by enlarging or increasing the passage, in the sound tube by means of a closing 20 member. The known devices of this kind, however, have the drawback that the individual oscillations of the closing member result in disturbing noises while at the same 25 time the adjustment is so complicated and difficult that it cannot be effected during playing.

The object of this invention is to avoid the 30 above defects by controlling the clear passage of the sound-box casing with the aid of two superposed disks having perforations which are adapted to register with each other. This is accomplished by making one 35 disk rotatable, that is to say, this disk is capable of oscillating about an axis so that its perforation more or less frees that of the other disk as will be more clearly understood from a description of the accompanying drawings, in which:

40 Figure 1 is a front view of the improved sound-box,

Fig. 2 is a partial elevation and vertical section thereof, on the line *a*—*b* of Fig. 1, and

45 Fig. 3 is a front view of a modified construction.

In the example shown, the casing A of the sound-box has connected to it a socket B which is provided with a box-shaped enlargement C, as best shown in Fig. 2. This 50 enlargement serves as the sound chamber proper of the sound-box. The sound-box itself is closed by a disk D which serves also as a carrier of the socket B. The disk D is

provided with perforations E through which 55 the sounds produced by the diaphragm F pass into the chamber C and by way of the socket B are transmitted to the tone-arm attached thereto, but not shown in the drawing.

Rotatably journaled above the disk D about an axis G is a second disk H provided with perforations I. The perforations in the disk H and those in the disk D are so located with regard to one another as to enable 65 the clear passage to be regulated by the rotation of the disk H.

The disk H is journaled about a relatively light axis or bolt G. This disk H is easily rotatable on the adjoining face of the disk 70 D. The disk H consists, by preference, of vulcanized fiber, felt or other material which is not liable to individual vibrations causing disturbing noises. In order to prevent oscillations of the disk H from being 75 transmitted to the disk D, provision may be made also between the two disks of a layer O of felt or like material. The contact, however, between the two disks may be insured by a weak spring K which is slipped 80 over the axis G.

In this manner, while safeguarding a reliable bearing of the rotary disk H on the stationary disk D, an easy rotation of the disk H and thereby a ready variation of the 85 free passage for the sound is at all times assured. By introducing through a slot L in the casing C a bent pin M into the disk H so as to serve as a pointer or indicator, the extent of the adjustment of the disk H with regard to the disk D may readily be read off 90 from a dial N on the sound-box. It is, therefore, possible to vary the strength of the tone in talking machines of this kind by merely adjusting the pointer N on the dial 95 and this may be effected even during the playing.

In the constructional example shown in Fig. 3, one of the disks is provided with three perforations E¹, E², E³, of gradually increasing diameter, thereby enabling the strength of the tone to be regulated from the finest pianissimo to the strongest fortissimo. To this end the second disk is provided with three perforations I¹, I², I³, of which the two 105 former perforations are in the shape of oblong slots in order to remain open during the whole passage.

In the constructional forms illustrated the axis G has a central arrangement, but it is obvious that it may have an eccentric arrangement, particularly in the case in which 5 the disk H is to perform merely an oscillating movement on the disk D.

I claim as my invention:

1. A sound box for talking machines in which the regulation of the tone is effected 10 by superposed perforated disks, comprising the sound box casing with perforated rear wall, a box shaped enlargement provided on the rear wall of the sound box casing and adapted to house a perforated disk, a central

shaft for said disk within the box and enlargement, and a spring on said shaft adapted to press the perforated disk against the perforated rear wall of the sound box. 15

2. A sound box for talking machines, comprising the sound box casing with perforated rear wall, a box shaped enlargement provided on the rear wall of the sound box casing, a central shaft within said casing and enlargement, and means on said central shaft 20 for regulating the tone. 25

Signed at Leipzig, Germany this 11th day of February 1915.

WALTER OPEL.
